PAUL NICOLAS LUCAS-GIRARDVILLE, OF PARIS, FRANCE.

METHOD OF STORING AND TRANSPORTING GASES.

Application filed May 18, 1926, Serial No. 110,021, and in France May 20, 192

This invention relates to a method of storing and transporting gases in the liquefied or solid state.

Liquefaction of gases is obtained, as is known, either by compression, or by cold, or by a combination of these two means.

Choice between the several processes is not however generally free. In the case of the so-called permanent gases, in fact the liquid

state, can only be obtained by bringing the gas to a very low temperature and keeping it there. In order to realize these conditions it is indispensable that the containers used be so arranged as to allow heat to pass only

very slowly. It is then possible in containers thus arranged to maintain the gas liquid at atmospheric pressure during a long time for intended practical applications, provided that the calories which pass through the cas-

ing are absorbed by the latent heat of evaporation of a small proportion of the liquid, which undergoes slow boiling. By thus accepting a certain hourly loss in the gas transported, it may be dealt with by leaving it at atmospheric pressure. However this method of transport necessitates that the containers be well protected against heat transmission, the more so because for the permanent gases thus transportable (oxygen,

nitrogen or methane) the temperatures which have to be maintained are extremely low. Consequently one is led to enclose the container in a casing as athermanous as possible.

The invention relates to casings capable of fulfilling these conditions. The ordinary heat insulators being as is well known insufficient to solve the problem in question, recourse is had to devices based on the principle of the Dewar double-walled flask, which has already been employed, after the first

applications to liquid air, oxygen and nitrogen. However the transport of large quantities of liquefied gas would lead, if the usual constructions were employed, to Dewar flasks of prohibitive dimensions, the difficulties and the costs of construction of which would constitute an insurmountable barrier.

According to the invention containers are used of suitable material, sheet iron for example, which are covered by a plating of multiple contiguous members, each of which has the characteristics of the Dewar flask (very high outer vacuum, highly polished surfaces, either silver or copper plated so

as to possess a very high reflecting power). The contiguity of these Dewar members, with the covering, if necessary, of the joints with members constituting a second protective layer, protects the inner container against heat almost as well as if it were made in one piece in accordance with the principles considered.

It is moreover to be noted that, for the transport of non-permanent gases, which can be liquefied by pressure alone and consequently remain liquid at the surrounding temperature, it is not the same thing whether the containers for transport be made with athermanous casings of the type above described or with ordinary casings.

It is in fact known that the vapour tension of gases thus liquefied increases very quickly with the temperature. One is thus led, even when they are provided with safety devices to prevent the pressure from increasing in an exaggerated way, to provide a resistance considerably greater than that which would suit the normal temperature of use. A considerable part of the gain in weight is thus lost (economy in first cost and in cost of freight).

If on the contrary these containers are made with athermanous walls, they may be constructed of much less weight, as it is known that the inside temperature, and consequently the pressure, will not vary much, even during a fairly long transport.

It will be observed finally that this system, combining light construction with the use of athermanous walls is equally applicable for the transport of permanent gases liquefied by the use of cold, if it be desired, to avoid loss by evaporation. If in fact protection against heat be efficiently obtained, the quantity of calories which enters the gaseous mass is fairly small, the rise in temperature of the fluid during the time of transport will not exceed a temperature sufficiently distant from the critical point, for the transport to be carried out in conditions of suitable security, provided of course that there is a suitable safety device for the case in which the pressure would become higher than the value corresponding to the resistance of the casing.

The employment of athermanous walls is also of a kind to afford particularly interesting advantages in special cases where two gases having different properties and boiling temperatures are to be transported.

The container for transport must naturally be made in a special way. For example it may be made in the following way as shown diagrammatically in the accompanying drawing.

An inner casing 1, not athermanous, contains one of the gases to be transported, for example methane, either liquefied or solid.

A second athermanous casing 2 surrounds the former at a certain distance in such way that there is circulating space 3 between the two walls. The bottom of the casing 2 is provided preferably with a cavity 4 which holds a reserve of liquid nitrogen. At the upper part is an opening 5 for the escape of the nitrogen vapour.

If a certain quantity of liquid nitrogen for example boiling at minus 195° be stored in the lower part of the container between the two casings the nitrogen vapour circulating between the two casings will maintain the inner body of methane at the like temperature. Now, methane solidifies at about minus 184°. It will thus be kept in the solid state so long as the nitrogen has not entirely evaporated. It will thus be possible to transport this gas or other similar gases solidified by cold in the same conditions of duration as if liquid nitrogen, oxygen or air were being transported.

These conditions of transport are particularly interesting in its application to aeronautics for example. In fact it is possible by means of suitable apparatus to liquefy and then to vaporize the methane carried by the aeroplane in containers of the kind hereinbefore described to suit the needs of the engine. These operations are carried out very easily owing to the very great difference of temperature existing between the body to be volatilized and the elements (air or exhaust gas) employed for the re-heating.

The quantity of methane thus volatilized to supply the engine being at each instant extremely small in comparison with the total quantity of fuel carried on board, the risks of fire resulting from a leak are themselves much reduced. They are the more so because the body remaining in the liquid state only during a very short time, the quantity of methane in question is vaporized and diffused instantaneously into the atmosphere, whilst a liquid such as benzene or petrol spreads into the cock-pit or gives off heavy vapours very dangerous from the point of view of fire-risk.

Even if, in the event of a bad landing, the container is burst, the methane being in the solid state does not instantaneously become liquid, which alone allows of a dangerous diffusion, and the firing of the engine is consequently cut off before a fire can have started.

Furthermore if the container constructed

as described on a fighting plane is pierced by a bullet, the methane being solid and continuing to remain so owing to the circulation of the nitrogen, there is no leak of fuel. Moreover even if it be an incendiary bomb since it passes through a layer of nitrogen before penetrating into the methane or re-entering the atmosphere after penetration, it cannot set fire to the fuel.

This protection from fire remains moreover very efficacious in the case of transport by tank wagons, especially in warfare. It is extended for such transport to highly inflammable liquid fuels such a petrol, alcohol and ether, for example, although these fuels have very low melting points (minus 98° for toluene, minus 130° for alcohol, minus 118° for ether); they can be violently frozen and kept in that state by the processes above described, so as to do away with fire risks in transport and storage both in times of peace as well as in times of warfare.

These double-walled containers may moreover be employed by means of an accessory device for the transport of gases which have not been brought into the liquefied state.

It is known that certain solid bodies, wood charcoal amongst others, have the property of absorbing a large volume of gas. Their ability to absorb depends both on the storage pressure and on the temperature of the charcoal at the moment of absorption. The temperature in particular has a very great influence on the proportion of gas absorbed; thus at the temperature of liquid air one volume of charcoal absorbs 135 volumes of hydrogen at atmospheric pressure.

If then the inner space of the double-walled containers above described is provided with a charcoal lining, the annular space being itself partly filled with liquid nitrogen, these containers will allow of the transport of hydrogen for example, under conditions as to weight, much more economical than those of the present systems of transport.

To sum up, this application of double-walled containers with an outer athermanous casing and circulation of liquefied gases between the two walls comprises the same improvements with the same advantages as the transport of gases liquefied or solidified by cold. Thus the principle of the double wall with circulation of nitrogen allows either of transporting a very great volume of hydrogen under a pressure of a few kilogrammes, or even of transporting a volume of it comparable with that which is contained in the usual cylinders, but working at a pressure slightly below that of the atmosphere, and therefore without risk of leakage or of fire.

The arrangements described can also be used for ordinary cold transport. In this case the athermanous casing delays heating

during a very long time, the difference between the outside temperature and that of the frozen provisions being much less great than in the case of liquid air and the passage 5 of calories being consequently less considerable.

Moreover the plant can be completed by placing between the two casings a certain quantity of brine or even of water, if one 10 is satisfied with maintaining a temperature above zero and lower than 10° or 15° , as is the case in the transport of certain fruits, of flowers etc. This quantity of water constitutes a reserve of cold sufficient, owing to 15 the arrangements described, to allow of keeping a cold storage wagon thus constructed for several days within the limits of temperature rendered necessary by the nature of the goods transported.

20 The same arrangements may be applied in the case of rooms or reservoirs in which there is maintained a temperature sufficiently low by a circulation of brine or other

cooling liquid. The use of the proposed system by considerably reducing the transmission of heat allows of the reduction to a considerable extent of the expenditure of motive power required operating the refrigerating plant in question. 25

Claim—

The method of storing a substance whose boiling point is below 0° C., in a condensed state such as a liquid or solid which comprises enclosing said substance in a heat conducting vessel which is in heat conducting contact with a liquid exposed to atmospheric pressure and maintained in a heat insulated vessel, said liquid having a lower boiling point than the said substance whereby the slow and gradual evaporation of the 35 liquid acts to maintain the said substance in its condensed state. 40

In testimony whereof I affix my signature.
